ASH RECEIVER

Rudolph F. De Boer, Grand Rapids, Mich., assignor to Applied Arts Corporation, a corporation of Michigan

Application April 6, 1936, Serial No. 72,927

4 Claims. (Cl. 206—19.5)

This invention relates generally to a container and more particularly is directed towards improvements in a retractable ash receiver of the type shown in my patent, No. 2,000,275, issued May 7, 1935.

One of the primary purposes of the present invention is to produce an ash receiver which has the portion carrying the ashes detachable only when it is in an open position. It will be appreciated that the frictional detachable mounting of the ash receiver proper, as shown in my prior patent, might accidentally become released when it is in its closed or retracted position and this is objectionable inasmuch as it prevents turning movement of the ash receiver proper and the shell in which it is mounted. Thus, considerable difficulty and annoyance is encountered in attempting to remove the ash receiver proper. The present invention absolutely eliminates any such difficulty inasmuch as the ash receiver proper can only be removed when it is swung to its wide open position.

Another primary advantage resides in the particular mounting means for holding the ash receiver shell onto the instrument panel. This means is located in assembled relationship with the receiver and this prevents loss thereof. Furthermore, no time is needed for assembling the same. Also, attachment to the instrument panel is accomplished by a simple rotative movement. It will be understood that the instrument panel only needs to have an opening cut therethrough. Thus, there are no problems involved in cutting or shaping integral portions of the instrument panel so as to provide supporting means for the ash receiver. This markedly eliminates expense.

Another feature of my invention resides in the particular frictional means whereby the ash receiver is frictionally held in any intermediate position and whereby it can be snapped to either its fully opened position or to its fully closed position.

Other advantages reside in the particular construction whereby economy in manufacture, so desirable in this type of installation, is attained.

In the drawing:

Fig. 1 is a front elevational view of the instrument panel, the ash receiver shell, and the ornamental front of the ash receiver.

Fig. 2 is a horizontal cross sectional view taken along the plane of the line 2—2 of Fig. 1.

Fig. 3 is a vertical cross sectional view showing the ash receiver swung to its open position.

Fig. 4 is a rear view of my device in assembled relationship upon the instrument panel.

Fig. 5 is a rear view of the ash receiver proper, the dotted lines indicating the opening through which the ashes are inserted.

Fig. 6 is a fragmentary plan view showing the upper end of the non-rotatable mounting shaft.

Fig. 7 is an underplan view of the lower end of the shaft.

Like numerals refer to like parts throughout the several views.

As shown in Fig. 3 of the drawing, numeral 10 indicates a substantially semi-spherical container, apertured and flanged at 11 to form an entrance for ashes or the like. A flanged back 12 completes the chamber. This back has a right angled encircling flange which contacts the inner side of the container's edge. Preferably it is spot welded in position. See Fig. 2. The front of the container 10 is highly plated as indicated at 13.

As clearly shown in Fig. 5, a hinge or bracket member 15 is welded at 16 onto the flat back 12. Upwardly extending lips 17 are integrally formed on the member 15 near each end thereof. These lips are curved as shown in Fig. 2. Intermediate these lips is a larger lip 18, having a boss 19, see Fig. 3, formed thereon. Both the lips 17 and 18 possess a limited amount of resiliency.

An ash receiver shell 20 is provided to house the container. This receiver 20 has a return 29 bent flange 21, see Figs. 2 and 3, and a hole 22 through its rear wall.

A yoke member 23, of semi-cylindrical shape, has a threaded opening 24 and a screw 25 extends through the opening 22 in the ash receiver shell 20 and threads into the threaded hole 24. The ends of the yoke member 23 abut against the rear side of the instrument panel 30. As shown in Fig. 4, the instrument panel 30 is cut away or notched at 31 whereby the yoke member may be inserted from the front of the instrument panel through the notches 31 and the circular opening 32 therebetween. See Fig. 4. After the yoke is inserted it is turned and the screw 25 tightened whereby the flange 21 is drawn tightly against the instrument panel. Thus attachment is had.

As clearly shown in Fig. 7, the ash receiver shell has a semi-circular groove 26 and consequently a semi-circular projection 27 is formed. This projection is depressed downwardly at 28 and a shaft 29 extends vertically through the ash receiver shell. This shaft is headed and squared as indicated at 35, see Fig. 6, whereby it is positively held against any rotative move- 55

ment. The ash receiver shell has inwardly extending bosses 36, see Figs. 6 and 7, at each end thereof. These bosses serve as anti-friction bearings for the ornamental front of the ash container proper.

This ornamental cover member 40 is flanged as indicated at 41. The shaft 29 extends through circular openings in the flange 41 and the projections 36 hold the ornamental cover in spaced relationship to the inner side of the shell whereby it is rotatably mounted. At one point the flange 41 is slit and bulged outwardly to form a projection 42, this projection riding in the slot 26 and limiting the movement of the ornamental cover plate. See Fig. 7.

The shaft 29 is cut away as shown at 39. See Fig. 1.

The ash container proper is adapted to be frictionally inserted into the ornamental shell 40 as shown in Figs. 2 and 3, a part of the outer surface 13 sliding interiorly of the flange 41. Also, the two end lips 17, see Fig. 3, pass on one side of the shaft 29 while the larger intermediate lip 18 passes along the outer side of the shaft, the boss or projection 19 passing through the cut away portion 39 of the shaft. As shown in Fig. 5, both the contacting portions of the container 10 and its back 12 are cut away at diametrically opposite points to permit passage of the shaft 29.

It is to be understood that the projection 19 and the lips 17 would not be able to pass around the shaft unless the same was cut away as described. This results because the several lips lack sufficient resiliency to permit this.

It will be apparent from the above description that the ash container proper is only detachable when it is rotated to the position shown in Fig. 2. Whenever it is rotated to more or less of a closed position the projection 19 and the lips 17 prevent disengagement and thus there is no danger of having the ash receiver accidentally become detached when it is positioned within the ash receiver shell. It is only when the ash receiver is capable of outward bodily movement at right angles to the instrument panel that its detachment may be had.

It will be understood that the instrument panel is merely formed to have the openings 31 and 32 therein whereupon the ash receiver shell and its yoke can be inserted therethrough after which the yoke is rotated to a position out of alignment with the notches 31. Next, the screw 25 is tightened. This causes a tight engagement between

the flange 21 and the front of the instrument panel. The flange 21 is of sufficient width to conceal the notches 31.

The ash receiver shell, oscillatably carrying the ornamental panel plate, colored to harmonize with the finish of the instrument panel, easily receives the attachable ash container by engagement between the several spring lips on the bracket 15 as previously explained. Disengagement when the parts are rotated to the relative positions shown in Fig. 2, is had by merely forcibly pulling outwardly upon the container, the flanged opening serving as a finger hold.

Having thus revealed this invention, I claim as new and desire to secure the following combinations and elements, or equivalents thereof, by Letters Patent of the United States.

1. An article of the class described comprising a shell, a shaft extending thereacross, an ash container, spring means fastened to the ash container and partially encircling the shaft in opposite directions whereby pivotal mounting of the ash receiver is obtained, said oppositely encircling spring means being axially positioned along the shaft and the said shaft being cut away adjacent one set of said spring encircling means whereby the ash receiver is attachable or detachable only at a certain circumferential position relative to said shaft.

2. In combination, a supporting means including a shaft having a portion thereof cut away, an ash container having means partially encircling the shaft in opposite directions, one of said sets of means being yieldable to a predetermined degree and one of said sets of means being in alignment with said cut away portion of the said shaft for the purpose described.

3. In combination, a mounting panel having an opening therethrough with oppositely disposed notches therein, a shell member having an open end receivable in said opening in said panel, means for preventing movement of the open end through said opening, a yoke member having its free ends spaced apart a distance equal to the distance between the said notches, means for pivotally mounting the yoke upon the shell so that the ends of the yoke contact the opposite side of the panel than that contacted by the aforesaid movement preventing means.

4. A combination of elements as recited in claim 3 in which means is provided for adjusting the yoke toward or away from the said shell.

RUDOLPH F. DE BOER.
